LOCK FOR SAFES

Wilfrid Lavallée, Longueuil, Quebec, Canada, assignor of one-half to Cyprien Ste.-Marie, Longueuil, Quebec, Canada

Application October 24, 1932, Serial No. 639,255

1 Claim. (Cl. 70—26)

The object of the present invention is to provide a mechanism which retards the opening of a safe door even after the proper combination has been used. Such a device is intended to 5 reduce burglaries in chain stores, cigar stores, gas stations and the like which are commonly robbed in broad daylight and where the success of the crime depends on quick opening of the safe and a prompt escape. It will be evident 10 that, in broad daylight, a retarded opening of the safe would cause the burglars to flee before the theft is completed.

The invention embodies a stop normally obstructing the door bolt from moving to release 15 position. By proper manipulation, the stop is set in motion towards a position which permits release of the bolt. This motion, however, is comparatively slow, whereby the opening of the door is delayed as above set forth. Preferably, 20 the motion is initiated by means of a wound spring but is retarded by an associated gear train and pendulum.

The invention is fully disclosed by way of example in the following description and in the 25 accompanying drawing in which

Figure 1 is a vertical section showing the clockwork;

Figure 2 is a section on the line 2—2 of Fig. 1;

Figure 3 is a perspective view of the safe;

30 Figure 4 is a detail section showing the escapement;

Figure 5 is a detail section showing the spring wind;

Figure 6 is a detail elevation of the pawl and 35 ratchet;

Figure 7 is an elevation of the locking bolt and associated parts; and

Figure 8 is a plan section of the safe door and locking bolt.

40 Reference to these views will now be made by use of like characters which are employed to designate corresponding parts throughout.

In Figure 3 is shown a safe 1 having a door 2 mounted on hinges 3. At the inner side of the 45 door is a locking bolt 4 adapted to interlock with the door frame 5 as shown more clearly in Fig. 8. The bolt is supported in part and operated by a stud 6 passing through a slot 7 in the door.

In order to prevent unauthorized shifting of 50 the stud, a hasp 8 is hinged at 9 to the door and apertured at 10 to receive the stud. The free end of the hasp fits over a staple 11 on the frame 5, and a padlock 12 is locked to the hasp.

55 The timing mechanism governing the opening of the safe door is enclosed in a housing 13 built

on the back of the door as shown in Fig. 2. It embodies a hub or stop 14 on which gear teeth 15 are formed. The bolt 4 is forked at 16 over the hub and has a finger 17 adapted to register with a slot 18 in the hub without passing therethrough. The hub has another slot 19 through which the finger 17 may pass to permit opening of the bolt 4. This slot is brought into register with the finger 17 in a given interval of time by means of a pinion 20 meshing 10 with the teeth 15 and driven, by means presently to be described, to rotate the hub 14.

It will be seen in Fig. 5 that a shaft 21 is journaled in the housing 13 and carries a dished gear 22 from which a journal 23 extends. The 15 gear 20 is keyed to this journal. The dished portion 24 of the gear 22 contains a spring 25 having its ends secured to the shaft and gear. The spring may be wound by means of a handle 26 on one end of the shaft. The other end of 20 the shaft carries a ratchet 27 engaged by a pawl 28 pulled by a spring 28' to prevent unwinding of the spring through the shaft.

The bolt 4 is normally moved by a spring 29 against the hub 14. The finger 17 normally 25 engages with the slot 18 to hold the stop or hub from rotating under the action of the spring 25 through pinion 20 and gear teeth 15. When the finger is withdrawn with the bolt by means of the stud 6, the hub 14 is free to turn under 30 spring action until the winder slot 19 is in position to receive the finger, whereupon the bolt moves to open position under the action of spring 29.

The action of the spring 25 on gear 22 and 35 pinion 20 is retarded by the mechanism shown in Figures 1, 2 and 4. A shaft 30 journaled in housing 13 carries a gear 31 and a pinion 32, the latter meshing with gear 22. Another shaft 33 in the housing carries a gear 34 and pinion 35, 40 the latter meshing with gear 31. Another shaft 36 carries a pinion 37 meshing with gear 34.

The shaft 36 also carries two star gears 37' and 38. Beneath the shaft 36, a pendulum 39 is pivoted at 40. The upper end of the pendulum 45 carries two arms 41 and 42 meshing with the star gears 37' and 38 respectively. The arms 41 and 42 serve as pawls intermittently arresting motion of the gear train and timed according to the period of the pendulum after the latter has once been swung by impact of the gears 37' and 38.

By this means, the movement bringing the slot 19 in line with the finger 17 to permit opening of the safe door, is delayed. The delay is suf- 55

ficient to discourage a hurried and speedy robbery. Thus, the invention finds its greatest utility in chain stores and the like which are usually robbed in broad daylight and where the success of the burglary depends upon a speedy opening of the safe and escape.

At the top of the door frame 5 is a slot 43 covered by a shield 44. Papers and other valuables may thus be dropped into the safe without opening the door.

Although a specific embodiment of the invention has been illustrated and described, it will be understood that various alterations in the details of construction may be made without departing from the scope of the invention as indicated by the appended claim.

What I claim is:—

In combination, a door, a slidable bolt adapted to lock said door, a rotary hub, a finger extending from said bolt towards said hub, a spring holding said finger against said hub, said hub having a recess adapted to interlock with said finger to prevent rotation of the hub and to obstruct movement of the bolt to release position, manually engageable means carried by said bolt for disengaging said finger from said recess, retarded means tending to rotate said hub and operative on disengagement of said hub and finger, said hub having a peripheral slot spaced from said recess and adapted to admit said finger, thereby permitting movement of said bolt to release position.

WILFRID LAVALLÉE.
